Patented June 11, 1918

UNITED STATES PATENT OFFICE.

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,269,419.

Specification of Letters Patent. Patented June 11, 1918.

Application filed August 25, 1915. Serial No. 47,353.

To all whom it may concern:

Be it known that I, FREDERIC P. GATES, a citizen of the United States of America, and residing at Hartford, in the county of Hartford and State of Connecticut, have invented a certain new and useful Improvement in Electric Switches, of which the following is a specification.

My invention relates to electric switches and particularly to multi-circuit switches, the object of my invention being to provide an improved switch mechanism of this type which may be conveniently employed for example to control independently the several lights of an electrolier group, although obviously the switch may be used for any purpose for which it is adapted.

In the accompanying drawings,

Figure 1 is a longitudinal section through a switch in which my invention is embodied in one form;

Fig. 2 is a section on the line 2—2, Fig. 1;

Fig. 3 is a section on the line 3—3, Fig. 1;

Fig. 4 is a detached perspective of certain 25 of the switch parts;

Fig. 5 is a partial section on the line 5—5, Fig. 2; and

Figs. 6 and 7 are perspectives of details.

In multi-circuit installations such as lighting circuits comprising several lamp groups, various switch devices have been employed to control the groups independently from a single switch mechanism. Perhaps the most common switch for this purpose is a rotary snap switch having a plurality of contact plates with wings variously arranged to connect the terminals of the lighting group in predetermined relation. Such a switch however necessitates the successive connection of the several groups both in attaining the lighting group which it is desired to use and in the eventual breaking of the circuit when it is desired to extinguish the light. In certain cases two push button switches have been employed in which one rotary switch plate, operated by a ratchet mechanism, is employed to make the successive connections, while another switch plate of oscillating motion is employed to interrupt or make the connection through the switch, as a whole. This mechanism is clumsy and inconvenient since it is not only necessary to operate the switch in such manner as to make the successive connections through the several groups in order to attain the desired lighting group, but it also in-

volves cutting out the lighting circuit through the oscillating switch bar, on each change in the lighting group. In still other switches, a plurality of push buttons are employed to effect the connections for the several combinations, while a single button serves to open the circuit (see Mann 876,207). But as in the switches previously mentioned, the circuit must be completed successively through the several combinations in order to obtain the last one, although in this construction, (as in the rotary snap switch,) there is no interruption of the lighting circuit between each change save such as is inherent in the shifting of the contact blades from one position to another. A switch of this character, however, is expensive to construct, unsightly in appearance and unsatisfactory to operate, since, in a dark position, it is difficult to see which of the several buttons should be pushed first, as the mechanism requires for its operation.

By the present invention, I have provided a combination switch having a switch blade controlling the connection of the switch as a whole with the main, and independent means for controlling the several lighting circuit combinations, the arrangement of the switch being such that the connection for a desired lighting combination may be established either before or after the connection to the main is made, while the connection to the main may be interrupted and the switch as a whole cut out without regard to the position of the switch controlling the lighting circuit combinations.

In the embodiment of my invention here illustrated, the present switch comprises a cup-shaped insulating body 10 of approximately the dimensions of an ordinary push button switch and adapted to be mounted in an outlet box by means of a yoke 11 secured to the upper face of the switch body 100 by the screw bolts 12 piercing the opposite ends of the latter. Depressed ledges 13 at opposite ends of the insulating body support the several wire terminals 14, 15, 16 and 17. The switch is of the single pole type and but one main is connected thereto, viz., at 14.

The interior of the switch body is divided, by an integral partition 18, into two switch chambers 19 and 20, the former containing the switch by means of which connection from the main is established to

the second chamber 20, in which is arranged the switch which controls the various lighting circuit combinations. The line switch here shown comprises a switch bar 21 adapted in the "on" position of the switch to span the space between the downwardly angled lug 22 integral with the base plate of the binding screw 14 and the co-operating switch terminal 23 which, in the form of an angled strap, leads from the switch chamber 19 to the switch chamber 20 wherein it presents two terminals 24 and 25 at different levels, for co-operation with the lighting circuit switch therein.

The line switch mechanism in the chamber 19 may be of any suitable type. I have here shown it as of the push button type described in the Peterson Patent 956,161, without the return spring (15) however. It embodies a switch arm 26 carrying the U-shaped switch bar 21 at one end and pivoted on the spindle 27 at its other end. The spindle 27 is mounted in a frame 28 secured to the base of the insulating body 10 by the screws 29 and having offset stops 30 which limit the extent of oscillation of the switch arm 26. A rocker bar 31 is pivotally connected to the shank 32 of the push button 33 and is journaled on the spindle 27. At its free end the rocker bar 31 carries a perforated abutment 34 against which bears one end of the switch spring 35 and through which passes the guide pin 36 for the spring. The opposite end of the pin has a T-head 37 which engages in a slot 38 in the shank of the switch arm 26. On the depression of the push button, the rocker 31 forces one end of the switch spring 35 past the axis of oscillation 27 of the switch arm 26 and at the same time compresses the spring 35, with the result that as soon as the axial point is passed, the spring expands and thrusts the switch arm 26 upward, thus establishing the circuit between the switch terminals 22 and 23. The switch in chamber 19 being thus closed, the current is now led through terminal 23 to the terminals 24 and 25 in switch chamber 20. In addition to these terminals 24 and 25, in switch chamber 20, there are in the present construction three other switch terminals in this chamber viz., 39, 40 and 41. The terminals 39 and 40 are on the same level with the lower terminal 25, connected with 23, while the terminal 41 is on the level of the upper terminal 24, connected with terminal 23. The terminal 39 is here formed as the offset lower end of the strap 42, the upper end of which forms the terminal plate for the binding screw 15. The switch terminal 40 in like manner forms the angled lower end of the strap 43, the upper end of which forms the base plate for the wire terminal 16. The switch terminal 1 is connected by screw 44

(Fig. 7) with a strap 45 let into the lower face of the insulating body 10 and connected by a screw bolt 46 to the terminal plate of the binding screw 17.

In a manner well understood in the art, three independent lighting circuits are severally connected to the three wire terminals 15, 16 and 17. Thus in an electrolier having seven lights, one light may be brought into the circuit by the wire connected at 15, three may be connected by the wire leading to the terminal 16, and the remaining three may be connected by the wire leading to the terminal 17. Any other desired combination may of course be connected up to the terminals 15, 16 and 17 and in fact another wire terminal may, if desired, be connected to the terminals 24-25.

Cooperating with the several terminals of the switch chamber 20 is a rotary snap switch mechanism comprising a pair of switch plates 47 and 48 of any desired predetermined number of contact wings, mounted on a common switch spindle and operated by a snap switch mechanism, not shown, since it is of common type. The switch plates are electrically connected together, although spaced vertically apart. The upper plate 47 as here shown has but a single contact wing 49, and is arranged at the level of the switch terminals 24 and 41. The lower switch plate 48 is provided with three contact wings 50, 51 and 52 and is arranged at the level of the terminals 25, 39 and 40. The connection between terminals 25 and 39, which may be called combination A, is secured through switch wings 50 and 51; 51 being in contact with the lower terminal 25, while 50 is in contact with the terminal 39. The terminal 52 at this moment will underlie the raised terminal 41, while the raised switch bar terminal 49 will overlie the switch terminal 40. The connection between terminals 25 and 40 (combination B) is secured, in the next position of the switch, by the terminals 50 and 52 which span the space between the terminals 25 and 40, while the switch wing 51 underlies the terminal 41, and the wing 49 overlies the terminal 39. This is the position illustrated in the drawing. The third combination (A and B together) is established through the switch wing 49 which now engages the upper terminal 24, while the switch wings 51 and 52 engage the terminals 39 and 40, while the switch wing 50 underlies terminal 41. The fourth combination (A, B and C together) is secured in the succeeding position of the switch, in which the switch wing 49 now contacts with the terminal 41, while wing 52 engages the lower terminal 25 and the wings 50 and 51 engage the terminals 39 and 40, thus bringing into circuit all three lighting connections.

As previously stated, the switch plates 47 and 48 are mounted upon a common spindle and operated by a snap switch mechanism of ordinary type. The switch spindle 53 and its button 54 however, are of novel construction. The spindle 53 embodies an upwardly extended shank of non-circular cross section and on which is slidably engaged the switch button 54, which has a well of suitable depth opening to its lower face to receive the upper end of the spindle. A ferrule 55 rigid with the lower end of the button 54 has a non-circular aperture through which the spindle passes, and is also provided with an external annulus 56 in which engage the inwardly extending pins 57 at one end of the rocker bar 58. The latter is pivoted on the pin 59 extending between the downwardly angled lugs 60 of the yoke 11 and engages at its opposite end the cross-pin 61 of the shank 32 of the push button 33.

It is obvious that through this arrangement the depression of the switch button 54 serves to shift the rocking lever 58 and thus to lift the button 33 and throw the live switch 21 into "off" position, breaking connection to the terminals 24—25 of the lighting switch. In either "out" or "in" position of the switch button 54, however, the engagement of the latter with the spindle 53 is maintained and the button 54 may be rotated to bring the switch plates 47 and 48 to the desired position, since the engagement of the pins 57, with the annulus 56 in the ferrule 55, permits the button 54 to swivel with relation to the rocker bar 58 at any time and whatever its position. Thus the desired combination for the lighting circuit may be established by the rotation of the switch button 54 while the latter is in its "in" position and the lighting circuit thereafter completed by pushing in the button 33 and thus throwing the switch bar 21 into "on" position.

Obviously the circuit may be broken, irrespective of the position of the switch plates 47 and 48, by merely pushing the button 54 in, thus throwing the rocker bar 58 in a direction to open the circuit at 21. The switch button 54 thus acts in a dual capacity as one member of a two-button push switch and as the rotary operating key for a snap switch. In order to facilitate its use as a snap-switch key, the outer end of the button 54 is preferably made non-circular, while the lower portion, which passes through the usual hole in the cover plate (not shown) is maintained in its usual cylindrical form to fill the face plate aperture and thus to prevent the entry of dust or dirt into the switch chamber.

Furthermore, to assist in determining the position of the switch plates 47 and 48 for the desired lighting combination while the main switch 21 is still "off," I prefer to pro-

vide some suitable indicating device to show the position of the switch plates. This may be accomplished in various ways, a simple one being by means of indicia or numerals on the end of the push button, as indicated at 62.

It is obvious that the switch may be used to control other multi-circuits than lighting circuits without departing from my invention and also that various modifications and details may be made without departing from what I claim as my invention.

I claim as my invention:—

1. An electric switch device, comprising a switch mechanism, a pair of push buttons for operating the same, one of said buttons being susceptible of rotation, an independent switch mechanism and an operative connection between the latter and said rotary push button.

2. An electric switch device, comprising a switch mechanism, a pair of push buttons for operating the same, one of said buttons being susceptible of rotation, an independent switch mechanism and an operative connection between the latter and said rotary push button, said connection being operative in either "out" or "in" position of the said push button.

3. An electric switch device comprising a switch mechanism, a pair of push buttons for operating the same, an independent switch mechanism having a rotary operating spindle, an operative connection between one of said push buttons and said operating spindle, said push button being capable of rotation to actuate said spindle.

4. An electric switch device comprising an insulating body recessed to form independent switch chambers, a carrying yoke spanning said chambers, independent switches mounted in said chambers, and an oscillating rocker carried by said yoke, together with means for independently operating both switches and engaging said rocker.

5. An electric switch device, comprising an oscillating push button switch, and a rotary snap switch, a pair of push buttons for operating the former and an operative connection between one of said buttons and the rotary snap switch, said button being susceptible of rotation to actuate the latter.

6. An electric switch device comprising a push button switch, a rock lever and a pair of push buttons for operating the same, a swiveling engagement between one of said buttons and the rock lever, in combination with an independent switch having a rotary operating spindle, in sliding engagement with said rotary push button, for the purpose described.

7. An electric switch device comprising an insulating base, a pair of snap switches arranged in series thereon, independent snap switch mechanisms therefor, and a common

- operating means for both switch mechanisms, said operating means serving to actuate either switch without affecting the other, and irrespective of the position of the 5 other.
8. An electric switch device comprising an insulating base, a pair of snap switches arranged in series thereon, one of said switches comprising a push button mechanism, and the other a rotary snap switch mechanism, together with a common operating means for both switches, said operating means serving to actuate either switch without affecting the other, and irrespective of 10 its position.
9. An electric switch device comprising a cup shaped insulating base, having its interior divided by an integral partition into a pair of switch chambers, a line wire terminal 15 extending into one of said chambers, a series of branch wire terminals arranged in the other switch chamber, a common terminal for both chambers, an oscillating switch serving to connect the line wire terminal with the common terminal, a rotary switch serving to connect said common terminal 20 with several branch terminals, and means for operating said oscillating and rotary switch mechanisms independently of each other.
10. An electric switch device comprising an insulating base, a pair of single-pole snap switches mounted thereon in series, a line connection to one of said switches, a plurality of branch circuits connected to the other switch and means common to said switches for operating the same independently of one another.
11. An electric switch device comprising a switch mechanism, a pair of push buttons for operating the same, a second independent switch mechanism and an operative connection between one of said push buttons and the second switch mechanism for operating the latter.

In testimony whereof I have signed my name to this specification, in the presence of two subscribing witnesses.
